KNITTING MACHINE

Harold E. Houseman, Laconia, N. H., assignor to
Scott & Williams, Inc., New York, N. Y., a
corporation of Massachusetts

Application July 24, 1936, Serial No. 92,278

25 Claims. (Cl. 66—140)

This invention relates to a knitting machine and particularly to yarn changing mechanism for such machine effective, for example, to change yarns frequently to produce horizontal 5 stripes.

Although it may be applied to various kinds of knitting machines, preferably those equipped with revolving needle cylinders, the yarn changing mechanism of the present invention is especially adapted to the so-called superposed cylinder type of machine illustrated in the patent 10 to P. A. Bentley, No. 1,713,736, dated May 21, 1929.

The type of machine illustrated in the above 15 mentioned patent is equipped with two needle cylinders arranged in axial alignment and adapted to revolve or oscillate in unison with each other. Each cylinder has associated with it a set of knitting cams and the cylinders carry 20 needles having hooks at both ends, which needles are adapted to be transferred at certain times from one needle cylinder to the other so as to be effective to knit rib stitches in the upper cylinder or plain stitches in the lower cylinder 25 to produce variable arrangements whereby, for example, a stocking may be knit with a one by one rib top, a six by three ribbed leg, and a plain sole with ribbed instep. The problems involved in designing a yarn changing device for this type 30 of machine are much greater than those encountered with the ordinary single cylinder type, since obviously no mechanism such as a yarn clamping and cutting device may be placed within the needle circle.

In the use of existing types of yarn changers 35 for such machines, it is necessary to substantially slow down the machine when each change of yarn is taking place. This not only slows down production, but involves the provision of driving 40 mechanism which is subject to considerable wear due to the numerous changes that must take place. In accordance with the present invention, there is eliminated the necessity for slowing down the machine because the yarns are 45 presented to the needles quickly and accurately by means of light mechanism independent of the heavier yarn fingers, which are permitted to have relatively slow movements consistent with their weight.

50 It will be obvious, however, that the yarn changing mechanism is adapted for use in other cases in which it is either impossible or undesirable to provide clamping and cutting mechanism within the needle circle, for example in 55 the case of knitting machines equipped with

wrap fingers located above the needles, from which there continuously extend yarns to the needles forming a closed cage.

The broad object of the invention is the provision of a yarn changing mechanism of the nature just indicated. Additional objects of the invention relating to details of construction will be apparent from the following description read in conjunction with the accompanying drawings, in which:

Fig. 1 is a plan view of a portion of a knitting machine of the superposed cylinder type showing the various elements for controlling yarn changes;

Fig. 2 is a fragmentary elevation of such machine partly in section showing primarily the selecting devices;

Fig. 3 is an elevation partly in section of certain details showing the mounting and actuating means for the yarn fingers;

Fig. 4 is a perspective view showing the various elements associated with the yarn fingers to introduce the yarns to the needles together with the actuating means therefor, certain parts being shown in section;

Fig. 5 is an elevation showing somewhat diagrammatically the elements for controlling the yarns during their presentation and removal from the needles;

Fig. 6 is a fragmentary elevation showing the clamping and cutting devices used in the present 30 yarn changing mechanism;

Fig. 7 is a side elevation of certain controlling devices for the yarn changing mechanism;

Fig. 8 is a fragmentary view showing certain 35 of the elements of Fig. 7 in an alternative position;

Fig. 9 is an end elevation showing the cooperation of the cam follower and cams of Figs. 7 and 8; and

Figs. 10 to 14, inclusive, are enlarged perspective views showing successive steps in a yarn changing operation.

Rotatable in the frame of the machine, which may be of the superposed cylinder type illustrated in the above mentioned Bentley patent, is a main drive shaft 250 to the end of which is fastened a bevel gear (not shown), which drives, through a cooperating bevel gear, the lower needle cylinder. The upper needle cylinder is driven in unison with the lower one by means of a vertical shaft and appropriate gearing. This type of drive is fully illustrated and described in the patent to P. A. Bentley No. 1,722,889, dated July 30, 1929, to which reference may be 50 55

made for details. The driving of the needle cylinders forms no part of the present invention. It is sufficient to indicate only that certain of the parts concerned with the present invention are driven by the shaft 250 in timed relationship with the needle cylinders.

A second shaft 251 is driven by shaft 250 through gears 252 and 253 of equal size. Both of these shafts revolve at the same rate of speed 10 as the needle cylinders. A third shaft 254 is revolved at half the speed of the needle cylinders through gears 255 and 256. Revolving on a stud in the frame of the machine is a ratchet wheel 257 to which is attached a sprocket wheel carrying the main pattern chain 72, which carries lugs 73 of five different heights, as will be pointed out in greater detail hereafter. A pawl 258 is pivoted to a bell crank 259 which rocks on a stud 260 in the machine frame and is provided with a follower roller 261 which, through the action of spring 262, is made to follow a double-lobed cam 263 on shaft 254 which causes the pawl 258 to advance the pattern chain at each revolution of the needle cylinders. As will be hereafter more 25 fully described, the pattern chain controls the selection of yarns.

Fastened to the top bed plate of the machine is a bracket 6 which carries the yarn changing mechanism, including the five yarn fingers 1, 2, 30 3, 4, and 5. These yarn fingers are mounted in bearing blocks at 7 and 8 and slide toward and away from the feeding position adjacent the needle cylinders, the feeding position of a finger being indicated by the active finger 4 in Figs. 1, 3, 35 4 and 10. Associated individually with the fingers are identical bell crank levers 9, 10, 11, 12 and 13, which are pivoted concentrically with each other and which engage downturned ends of the fingers as indicated in Figs. 1 and 3. When 40 these levers are moved in a counter-clockwise direction they withdraw their respective fingers from active position to which they are urged by by compression springs 14, 15, 16, 17 and 18. These 45 springs surround the fingers and serve to move their corresponding fingers into yarn feeding position when the various bell crank levers holding them out of action are released.

Associated with the five bell crank levers 9 to 13 are five identical detent levers indicated at 50 23, each of which is arranged to cooperate with one of the bell cranks. The various detent levers 23 are pivoted at 19 and are urged by springs 28 against an adjustable eccentric stop pin 29. The detents are arranged to engage the ends of the bell crank levers after the levers have been moved to withdraw their respective yarn fingers whereby the yarn fingers are retained in inactive position against the actions of their springs.

Two rods 30 and 31 are slidably mounted in 60 bearings in the bracket 6 and carry a frame 32 to which they are pinned. This frame carries five levers 37 pivoted upon a shoulder screw 38 secured to the frame, which levers embrace a stop pin 39 so that their swing is restricted to a 65 small arc. Springs 44 urge the levers 37 in a counter-clockwise direction against the stop pin 39, which is located so as to cause the pointed ends 54 of the levers to align with notches 43 in the bell crank levers. The frame 32 is normally 70 held in a forward position by the engagement of an adjustable headed latching screw 45 mounted on a yarn change selector lever 46 with a projection 47 on the frame 32. This selector lever 46 is pivoted on a screw 20 fastened in the bracket 6. 75 Whenever a yarn change is to take place, the

latching screw 45 is raised and the frame 32 may then be moved back by a spring 333 (Fig. 7) to be later positively advanced by means hereafter described. Mounted on each of the detent levers 23 is a latch 48 pivoted thereto at 49 and held by a spring 50 against a stop pin 51.

The five levers 37 are identical, each having three extensions indicated at 52, 53 and 54, the last of which is pointed, as previously described. The extensions 52 may be engaged by a selector 10 cam 55 adjustably mounted on the selector lever 46, such engagement taking place when the frame 32 carrying the levers 37 is moved backward. The operating lever thus engaged is swung in a clockwise direction against the pull of its spring 15 44. This places its shoulder 53 in position to engage the latch 48 and as the lever 37 continues to move backward its shoulder 53 engages the latch and swings it about its pivot in a counter-clockwise direction and passes behind it so that 20 no movement is imparted to the corresponding detent lever 23. However, on the forward movement the shoulder 53 again engages the latch 48, which is now restrained from swinging clockwise by the stop pin 51 with the result that the 25 detent lever 23 will be swung in a clockwise direction far enough for it to disengage the corresponding bell crank lever which it has been holding. The corresponding yarn finger will then be 30 snapped by means of its spring into feeding position. The cam 55 is arranged with respect to the extensions 52 so that it is not cleared by these extensions when the frame 32 reaches its most backward position. As the operating lever 37 continues to move forwardly, the extension 52 35 passes beyond the selector cam 55, after which, unless another yarn change is to take place in the next course of knitting, the selector lever 46 falls to its lowest position permitting the latch screw 45 to hold the frame 32 together with the 40 operating levers in the forward position. Meanwhile the operating lever 37 last selected lies against the end of the corresponding bell crank lever. When another selection is made and the 45 levers moved back to their furthest extent, the lever 37, which is not again selected, is moved counter-clockwise by its spring 44 against the stop pin 39 and comes into alignment with the 50 notch in its bell crank lever so that, on the forward movement, its extension 54 will engage this notch and rotate the bell crank lever, thereby withdrawing the corresponding yarn finger from feeding position. As this bell crank lever reaches the end of its movement, its end engages detent lever 23, first swinging it to the right and then 55 passing slightly beyond its shoulder with the result that the detent lever moves back into position to engage and retain the bell crank lever and thus hold its corresponding yarn finger in inoperative position.

As it is desirable that each of the five yarn fingers should feed from substantially the same position, it is necessary, in making a yarn change, to partially withdraw the feeding finger before snapping another into the position previously occupied by that finger. As a consequence, the operating parts are so designed that as the frame 32 moves forward after having completed the backward movement, the operating lever 37 which is associated with the active yarn finger engages its bell crank lever and withdraws its finger a substantial distance before the newly selected operating lever trips its detent to permit the finger which it controls to snap into feeding position. As the fingers must pass into and out of action 70 75

without striking each other, their yarn feeding ends are made to follow separate paths. These paths are controlled by means of slots 40 in a plate 56, which slots embrace pins 41 extending from T-shaped pieces 42 into which the two portions of each of the yarn fingers are threaded. The slots 40 are shaped as indicated in Fig. 3, which shapes indicate the paths followed by the yarn finger ends. The middle finger 3 moves in a straight line. The lower fingers 1 and 2, as they move back, travel for a short distance in straight lines but then move down and backwardly and finally straight back. The upper fingers 4 and 5 move upwardly instead of downwardly during their backward movements. Each of the yarn fingers is made of two bent rods which, by adjustment in the T-shaped pieces 42 in which they are held by lock nuts, may be finely adjusted and held in such adjusted positions. Screws 57, 58, 59, 60 and 61 serve as stops for the five bell crank levers and accordingly for the yarn fingers. Individual finger adjustments in and out are made by turning these screws, which are held in adjusted positions by clamp screws. The means for advancing the frame 32 and the five operating levers 37 carried thereby to effect a change of yarns will be clear from a consideration of Figs. 7 to 9. Fastened to the shaft 251 which rotates once for each revolution of the needle cylinders, is a cam carrier 201 on which are mounted two cams 68 and 69. The cam 69 has a thin portion 690 and a thick portion 691, while the cam 68 is secured to the cam 69 against the thin portion 690 thereof and forms, at its rearmost portion, a continuation of the thicker portion 691, as will be clear from a consideration of Fig. 9. The cam 68 extends as indicated in the figures beyond the forward portion of the cam 69 and carries a roller withdrawing cam 70. The cam arrangement just described imparts movement to the frame 32 by means of a double-armed lever 202 pivoted at 203 to the frame of the machine. The lower arm of this lever carries a roller lever 64 pivoted to it at 65 and urged by a spring 67 reacting between an eccentric post 45 and the upright arm of lever 202 in a clockwise direction to cause the roller 204 carried by the lever 64 to move inwardly to ride at proper times the portion 690 of the cam 69. Movements of the lever 64 are limited by means of a shoulder screw 66 projecting through an enlarged opening in the lever 64. An adjustable screw 71 is carried by the outer end of the lever 64 to be engaged by the cam 70 at certain times. The upper end of the lever 202 carries a screw 62 designed to abut a pin 63 extending from the frame 32. The adjustment at 62 is made such that when the roller 204 is on the high part of the cams 68 and 69, the carriage 32 is advanced sufficiently to cause the bell cranks 9 to 13 to clear the shoulders of the detents 23.

If the machine is running with one yarn being fed through a series of courses, then during about half of each of those courses the frame 32 rests in its forward position, being retained therein by engagement of the projection 47 with the head of screw 45 carried by the selector arm 46. Under such conditions the lever 202 remains in such position, due to the weight of the lower arm and the parts carried thereby, that the screw 62 remains in engagement with the pin 63. The roller 204 is then in such position relative to the shaft 251 that the screw 71 will not be engaged by the cam 70. As a result of this, the spring 67 holds the roller in position to be engaged by the high

portion 692 of the thin portion 690 of cam 69. When the roller is engaged by cam portion 692, the lever 202 will be rocked slightly counter-clockwise, moving the frame 32 to such extent as to provide a slight clearance between projection 47 and latch 45. This action is illustrated in Fig. 7. The clearance so produced will be maintained until the roller 204 can ride off the trailing end of cam 69 whereupon the frame 32 settles back under the action of spring 333 to re-engage projection 47 with latch 45. So long as no yarn change is to be effected, this slight movement of the frame 32 occurs in the formation of each course without effecting any results except a slight movement of the bell cranks 9 to 13 which corresponds to inactive yarn fingers.

The purpose of this action is to free the lever 46 so that no restraint is offered to its movement by one of the lugs 73 on the pattern chain. It is just after the high point 692 engages the roller 204 that the action of a lug on the follower 74 of lever 775 takes place to raise, through the medium of link 78, the lever 46 to an extent determined by the height of the pattern lug. It may be noted that overrun of the lever 46 is prevented by a stop screw 80 engageable with a fixed lug on the frame 6.

When the selector lever 46 is elevated by the rather sudden action of a lug 73 on follower 74, it invariably overruns and vibrates. The maintenance of separation between 45 and 47 through substantially a half revolution of cam 251 gives the lever 46 and its cam 55 sufficient time to settle into a position of rest before any projection 52 of a lever 37 moves back to engage it.

When a selection takes place, the lever 46 rises to a predetermined position depending upon the height of the lug 73 and then, as the roller 204 passes off the end of cam 69, the frame 32 is moved backwardly by spring 333, causing one of the extensions 52 to engage the cam 55, which will, at this time, have come definitely to rest. The lever 202 will now be rocked by the spring 333 so that its roller 204 moves inwardly, following the trailing end of cam 69 until the limit of outward movement of the frame 32 is reached by the engagement of roller 204 with the lowest point of the cam 69. The fingers 37 now effect the results described above on their outward movement. As the rotation of shaft 251 proceeds, the roller 204 will now ride up the forward extension of cam 68, causing the frame 32 to move forwardly. The roller 204 will remain in its inner position in which it would engage portion 690 of cam 69 until the cam 70 engages screw 71, whereupon the lever 64 will be rocked outwardly, moving the roller 204 into an outward position in which it will fail to be engaged by the portion 690 of cam 69 and consequently will continue to follow the active edge of cam 68, finally attaining its outermost position at 680 corresponding to the location of the frame 32 in its extreme forward position. The effect of the action of cam 70 upon pin 71 will be clear from Fig. 8, in which the cam carrier 201 is shown in the same angular position as in Fig. 7 but the parts are indicated in the relationship they take when a selection occurs. When the roller 204 reaches 680, it will be obvious that it can again move inwardly under the action of spring 67. If no selection is to take place in the next course, a plain link of the chain 72 will pass under the follower 74 and consequently the arm 46 will drop, bringing the cam 55 below the lowermost level of any of the levers 37 and also bringing the screw 75

head 45 into position to be engaged by projection 47. Thereafter, when the roller 204 leaves contact with cam 69, the frame 32 will be retained in its forward position by engagement of 47 and 5 45 and the action of the cam 69 referred to above will take place until another selection is to be effected.

The selector lever 46 normally rests upon a stop screw 79 with its latch 45 engaged with 10 projection 47 and with the selector cam 55 below the lowest operating lever 37. When any one of the five heights of chain lugs 73 rides under follower 74, the selector cam 55 is elevated to select the corresponding operating lever. 15 When a pattern lug passes from under the follower 74, a spring 264 lowers the selector lever 46. The selector cam 55 is purposely made as thick as possible without permitting it to engage more than one operating lever at a time, so that the selected positions will not need to be too exact. 20 The link 78 is made in the form of a turn buckle so as to provide adjustment. In order to secure a strong arrangement in view of the considerable distance between the cam 55 and the pivot 20 of lever 46, an eccentric 81 is threaded into the end of latch 45 and is arranged to engage a bearing plate 83 secured to the frame, the eccentric being held in adjusted position by a lock nut 82 (Fig. 1). From the foregoing it will be seen that by 25 setting up the proper pattern lugs 73 in different ways, the yarn fingers may be made to go into feeding position in the desired sequence, the fingers going into and out of action without interference with each other. It will be noted that 30 a yarn finger which is in action will be withdrawn to a considerable extent before another finger is snapped into action by the tripping of a detent 35 23. The changes thus effected take place comparatively slowly throughout the rise of the cam 40 68, which is so gradual that quite heavy parts may be moved readily without excessive vibration and failure to assume definite positions. Obviously, however, means must be provided for causing the yarns to go into and out of action on 45 definite needles, and there will now be described the elements associated with the yarn fingers and their comparatively slow changing means to insure that precise insertion and removal of the 50 yarns may be effected.

50 Mounted on the bracket 6 is an auxiliary bracket 84 to which is fastened a stationary shear blade 85. A movable shear blade 86 is pivoted on a screw 87 and is held in contact with the stationary blade 85 by means of a flat spring 55 88 mounted between it and the head of screw 87. Underlying the rearwardly extending arm of the movable blade 86 is an L-shaped yarn clamping lever 89 pivoted at 90. This yarn clamping lever 89 is faced with leather at 890, where it is adapted 60 to bear against a serrated plate 91, between which plate and the leather facing the inactive yarns are to be clamped. The leather facing of the clamp 89 sinks into the serrations in the plate 91, crinkling the yarns and affording a more 65 positive clamp. A strong spring 92 operating on the shear blade 86 serves the dual purpose of closing the shears to cut yarns and exerting a tension on the yarn clamping lever 89. The 70 grooved, or serrated, yarn clamping plate 91 carries an L-shaped flat spring clamp 96 (Fig. 1) which is fastened by a screw 97. The free arm of this clamp is split to form a forked end with the two resulting portions resting in adjacent grooves of the plate 91. The ends extend slightly 75 beyond the edge of the plate 91 and are up-

turned, as indicated most clearly in Figs. 10 to 14, inclusive, to engage a yarn which is going out of action. This light spring clamp serves as a yarn retaining clamp when the main clamp 89 is open to permit yarns to enter or leave.

The yarn clamp 89 has a downwardly extending arm below its pivot 90. A lever 93 pivoted at 94 carries a pin in which is secured an adjustable screw 95 bearing against this downward extension of the clamp. The lever 93, when rocked counter-clockwise, opens the clamp 89 and also the shears against the pull of spring 92.

The clamp and cutter operating lever 93 carries at one end a lever 98 which is pivoted at 99 and is urged against a stop pin 100 by a spring 101. Pivoted on the main bracket 6 at 102 is a four-armed lever 103. One arm 104 of this lever carries an adjustable screw 105 which bears against the inner end of rod 31. A spring 106 keeps screw 105 in contact with rod 31 as it moves backward and then forward, whereby lever 103 is oscillated about its pivot 102. On an arm 107 of lever 103 is mounted a cam 108. When the lever 103 is moved by rod 31 in a clockwise direction, the cam 108 will engage the lever 98 on the lever 93 through which, because lever 98 engages pin 100, the lever 93 will be rocked to open the clamp and cutter and then, as cam 108 passes beyond the lever 98, will be freed so that spring 92 may effect the clamping and cutting of the outgoing yarn. On the other hand, as lever 103 moves in the opposite direction when rod 31 moves backwardly prior to a change of yarn, the cam 108 swings the lever 98 against the action of light spring 101 and passes it, imparting no movement to the lever 93. A stop 305 engages a lug on lever 93 to restrict its movement in a clockwise direction.

In view of the comparatively slow action of the yarn fingers referred to above, there are provided light means for effecting quick shifts of the yarns to secure accurate insertion and withdrawal of the yarns to and from definite needles. For actuating these last named means, there is mounted on the supplementary bracket 84 a three-armed lever 109 which is pivoted at 110 on a horizontal axis. Clamped in the top and bottom of this lever are pins 111 and 112, which will be respectively referred to as upper and lower yarn blocking pins. The yarn-controlling ends of these pins are close to the yarn feeding end of a yarn finger when it is in active position, and lie behind a yarn guarding plate 113 which is positioned slightly above the clamp plate 91. The yarn guarding plate 113 and the clamp plate 91 provide between them a space within which the yarns move in going into and out of action. The lever 109 carries a stop screw 114 which normally engages the frame to hold the lever 109 in an extreme clockwise position to which it is urged by spring 115. Under these conditions the lower blocking pin 112 extends upwardly through a slot 191 in clamp plate 91 and beyond the under surface of the yarn guarding plate 113, as indicated in Fig. 5. The lever 109 is rocked during a yarn change about its pivot a sufficient distance to cause the end of the lower pin 112 to pass below the upper surface of the clamp plate 91 and bring the end of the upper pin 111, which is positioned in overlapping relationship with, and close to the end of, the lower pin 112, down within the slot 191 in the plate 91. The rocking of the lever 109 is caused by a screw 116 having a rounded head acting as a cam and riding under a lever 118 pivoted at 119 to the blocking pin lever 109. The lever 118 functions somewhat similarly to the

lever 98 previously described, being urged by a spring 120 against a stop pin 121 so that as the screw 116 passes to the right as indicated in Fig. 5 it will rock the lever 118 against the light spring 120 and pass it, whereas, in moving in the opposite direction, it will engage the lever 118, which is now backed up by the pin 121, and thereby effect a counter-clockwise rotation of the lever 109. The screw 116 is carried by one of the arms 111 of the lever 103. The blocking pins 111 and 112, the operation of which will be more fully described hereafter, are provided to maintain a yarn in a substantially constant feeding position as its finger is being retracted until after a new 15 yarn has been introduced.

When a yarn finger is tripped into feeding position, its yarn extends from the feeding eye to the main clamp 89 and this extended portion of the yarn is not close enough to the needles to be 20 engaged by them. A yarn placer is accordingly provided which engages the yarn of any finger which has been tripped into feeding position and extends it to a point close enough to the needle cylinders to enable the needle latches which are 25 being closed by the knitting loops at this point to seize it. It makes no difference whether needles are knitting in the upper or rib cylinder or in the lower cylinder or, alternately, in both. Any one of them is capable of seizing the yarn as 30 it is swung over to them. The yarn placer comprises a flat lever 122 which is reduced in width at its free end terminating in a hook 192 for engaging the yarn which is to go into action. The lever 122 is pivoted at 123 in a lever 124 which 35 swings about a pivot screw 125 secured in the bracket 84. A spring 127 normally holds the lever 124 against a stop screw 126 (Fig. 1). A lever 128 pivoted at 131 in bracket 84 is provided with four 40 extensions. The lever 128 is normally held by a spring 132 so that a stop screw 133 in one of the extensions rests against a lug formed on the bracket 84. On another extension of lever 128 is a screw 134 which is adapted, when lever 128 is 45 swung in a counter-clockwise direction, to contact with lever 124 to swing it and the placer 122 in a clockwise direction. An adjustable stop screw 135 limits the swing of lever 124 and thereby the placer hook 192.

On a third extension of lever 128 is secured 50 a cam 129 having two active arms which embrace the placer 122 above its pivot 123. When lever 128 is in the normal position mentioned above, cam 129 holds the hook 192 which is positioned behind the yarn guard 113 up so that it is 55 above the level of the under side of this yarn guard. When lever 128 is swung, screw 134 moves a short distance before contacting with lever 124 to swing lever 124 and placer 122. The initial movement of lever 128 before this contact takes 60 place permits the cam 129 to force the placer hook 192 straight downwardly into engagement with screw 136 before it is swung laterally to engage the ingoing yarn. The hook is held against the adjustable stop screw 136 by the light spring 137 as the lateral swing takes place and it moves 65 out of control of cam 129. The adjustment of this stop screw 136 alters the height of the placer hook and the adjustment may be made so that the yarn is presented to the closing needle latches at the proper level. When the lever 128 returns 70 to normal position, the cam 129 again engages the placer and elevates its hooked end. It is preferable to move the placer hook 192 straight down before it swings laterally so as to be certain that the hook is down to the yarn engaging level

before the yarn is engaged in the lateral swing.

On the fourth extension of lever 128 is a lever 138 pivoted at 139 and normally held by a spring 140 against a stop pin 141. A cam 142 on an upper arm of the operating lever 103 engages 5 the lever 138 to rock its lever 128 to thereby swing the placer 122 when lever 103 is moved forward by rod 31. On the backward movement of lever 103 the cam 142 may swing the lever 138 against the action of light spring 140 without 10 imparting any movement to the lever 128.

It will be noted that the rise of the cam 68 is not uniform but is stepped as clearly indicated in Figs. 7 and 8. These steps are so arranged and the cams 108 and 142 and screws 116, 105 15 and 62 accurately adjusted that the operations of the various parts just described occur in closely timed relationship to secure the proper sequential operations of the various yarn controlling elements to obtain the proper actions. These operations will now be described in detail in connection with Figs. 10 to 14, inclusive, which indicate successive steps in the effecting of a yarn change, which steps take place in extremely rapid succession in the operation of the machine. The 20 parts which must have accurate movements, however, are so light that despite the rapidity with which the various actions follow each other, the proper sequence is always followed to secure an accurate yarn change on the desired needles. 30

The various figures, with the exception of 8 and 11 to 14, inclusive, are consistent with the normal feeding of a yarn from finger 4 to the needles. The finger 4 occupies the position illustrated particularly in Figs. 1, 4 and 10, the 35 yarn extending therefrom tangentially to the circle of needles N to be seized by the hooks of needles in either the upper or lower cylinder. The yarn so extending will clear the lower blocking pin 112.

During such feeding of the yarn the frame 32 will be held in its forward position by the latch screw 45 on the selector lever 46 engaging the projection 47, the lever 46 being in its lowermost position. Upon each revolution of the cylinder, 45 however, at the proper time as determined by cam rise 692, the carriage will be moved slightly further forwardly, providing a clearance between latch 45 and projection 47 but effecting no other material condition. The bell crank 12 corresponding to yarn finger 4 will be in the position shown in Figs. 1 and 3 resting against its stop 60, whereby the finger is held in properly adjusted forward position. The lever 37 corresponding to the bell crank 12 will rest against the bell crank as illustrated in Fig. 1, being urged into such position by its spring 44. The remaining levers 37 will rest within the notches 43 of their corresponding bell cranks, which are held to retract their yarn fingers by latches 23. The clamp 89 and the cutter will be closed, the idle yarns being clamped by 89 and also being located beneath the tines of the spring clamp 96. 65

Assuming that the finger 5 is to be brought into action and the finger 4 out of action, the condition existing in Fig. 7 will be first attained, namely, the roller 204 will ride upon the high portion 692 of cam 69, producing a clearance between latch 45 and projection 47. Immediately after this clearance is provided, a lug of the greatest height on the pattern chain will ride under the follower portion 74 of lever 75, rocking the selector lever 46 upwardly to bring the cam 55 to the level of the uppermost lever 37. As mentioned previously, this action is followed by 70 75

a dwell in the selecting parts to give the cam 55 time to come to rest in the position determined by the lug on the pattern chain, this dwell occurring until the roller 204 starts down the trailing slope of cam 69. As the roller 204 follows the trailing slope of the cam, the lever 202 is forced clockwise by the spring 333 secured to the frame 32 and the frame with its associated levers moves outwardly to make a rearward stroke.

During this rearward stroke the lever ends 108 and 142 and the pin 116 pass the yielding levers 31, 138 and 118 as the lever 103 follows the rod 31 under the action of spring 106. The levers 15 31 move back with the frame 32. The lever 31 corresponding to the yarn finger 4 will pass the yielding lever 48 without tripping its detent lever 23 and will ultimately pass below the bell crank 12 and be snapped to its left hand position, as 20 viewed in Fig. 1, by its spring 44. During the same rearward motion the projection 52 on the uppermost lever 31 will engage the cam 55, whereby this lever will be moved clockwise against the action of its spring 44. During such movement it will engage the lever 48 on the uppermost 25 latch 23, which lever will yield to permit it to pass. When the frame 32 reaches its outermost position, the projection 52 will still be resting upon the cam 55.

30 The roller 204 will now begin to rise up the slope 68, moving the frame 32 forwardly. In going up the slope 68, the pin 71 will engage the cam 70 just before the roller reaches the initial rise of cam 69 with the result that the roller will be forced outwardly and will fail to engage the cam 69 and so continue to follow the rise of cam 68.

The first event in the forward movement of the frame 32 consists of the engagement of the 40 end of the second lever 31 within the notch 43 of bell crank 12, causing the bell crank to be rotated counter-clockwise to start withdrawal of the yarn finger 4. As the finger 4 moves rearwardly, its yarn feeding end will rise upwardly 45 due to the cam slot 40 and the finger will then continue to move in a straight line rearwardly. This movement gets it out of the path of the finger 5 which is to be introduced. As the finger 4 moves rearwardly and upwardly, its yarn will 50 be drawn about the blocking pin 112 and upwardly against the yarn guarding finger 113, which, as stated previously, overlaps the pin 112 when the latter is in its uppermost position. The blocking pin 112 is only slightly outward of the 55 needle cylinder as compared with the feeding position of the yarn finger 4 (and the other yarn fingers) and consequently the yarn will continue to feed to the needle circle to be taken by the needles. As the movement of frame 32 continues, the projection 53 on the uppermost finger 60 31 will engage the lever 48, which is now backed up by pin 54 and effectively becomes a unitary part of its carrying latch 23. Before the projection 52 clears the cam 55, the uppermost latch 65 23 will be swung to the right, clearing the bell crank 13 and permitting the spring 18 to snap the finger 5 forwardly and then downwardly to the normal yarn feeding position. The uppermost finger 31 will thereafter clear the cam 55 and 70 be swung to the left by its spring 44 to rest against the right hand face of the bell crank 13. It will be noted that as soon as the cam 55 is cleared by the portion 52 of a lever 31, it may then be again selectively moved by a lug 73 on the pattern

chain to possibly effect another yarn change in the next cycle of operation.

When the finger 5 is snapped into its feeding position, the parts are in the condition illustrated in Fig. 11, the finger 4 being partially retracted 5 so that its yarn is carried about the blocking pin 112 while the yarn to the finger 5 will pass about the rear of the blocking pin 112 extending from the clamp 89. There is a dwell on the rise of cam 68 at this time to permit the introduced 10 finger to settle in its new position.

As the frame 32 moves forwardly upon continued rise of the cam 68, the lever 103 is rocked clockwise as viewed in Fig. 1. Engagement of the lever end 142 with lever 138 now takes place, 15 and since 138 is backed up by pin 141, its carrying lever 128 is rocked counter-clockwise. In the first portion of this rocking movement the cam 129 forces the placer finger 122 downward so that this finger is depressed from its previous 20 position to the position indicated in construction lines in Fig. 12, in which its hook 192 is located slightly below the level of the clamp plate 91. Thereafter the screw 134 engages lever 124 and causes it to rock clockwise so that the placer 25 25 engages the yarn from finger 5 and carries it forwardly as illustrated in Fig. 12.

Before the placer hook 192 attains its most forward position, namely, just about the time it has attained the position indicated in Fig. 12, the 30 pin 116 acts upon lever 118 now backed up by pin 121 on the blocking pin carrier 109. As a result, a quick downward movement of the blocking pins 112 and 111 takes place. The pin 112 in dropping below the level of the clamp plate 91 clears 35 the yarns from both fingers 4 and 5. The yarn from finger 5 accordingly extends directly between the eye of the finger and the placer hook 192, while the yarn from the withdrawing finger 4 extends about the blocking pin 111 and thence 40 to the needles, and continues to feed in a substantially normal manner.

The placer hook 192 now reaches its forward-most position (Fig. 13) and causes the yarn from finger 5 to be engaged by the needles. The clamp 45 89 should not release the ingoing yarn from finger 5 until after the yarn has been seized by the first needle with which it is engaged and carried down into the fabric to form the first loop of that 50 yarn. If the clamp is opened too soon, the yarn 55 is likely to be pulled sidewise out of the spring clamp 96, drawing other inactive yarns out with it. By slightly delaying the opening of the clamp 89 until the time just indicated, a slack loop is formed by the ingoing yarn, which is taken up as 60 the needle which first engaged it travels around with the cylinders, with the result that the end of the ingoing yarn is drawn out of the rear of the pinch clamp 96 without appreciably displacing the other yarns held therein. The opening 65 of the clamp is quite critical, since if it is opened too late, the ingoing yarn will be broken off.

The yarn from the withdrawing finger 4 has 65 snapped backwardly over the upper end of the pin 112 but engages the blocking pin 111 which now projects into the slot 191 of the clamp plate 91. It continues to feed several needles beyond the one on which the new yarn has been entered, producing the necessary overlap.

Practically simultaneously with the opening 70 of the main clamp 89 and, of course, the cutter blade 86, the blocking pins are swung upwardly as the screw 116 clears lever 118 and the yarn from finger 4 snaps rearwardly to occupy the most direct position between the last needle 75

with which it is engaged beneath the guard 113 and the now substantially fully retracted finger

4. If the placer hook 192 was in its lowered and forward position, it would be engaged by the 5 withdrawing yarn and impede its withdrawal. Since it is practically impossible to cause it to move rearwardly out of the way to avoid this movement, it is so arranged that in the very beginning of its withdrawing movement it will 10 engage the upper surface of the opened clamp 89 and be cammed upwardly thereby against the tension of spring 137. The withdrawing yarn accordingly passes beneath it and it ultimately reaches its initial rest position which brings its 15 hook end above the guard 113.

The position attained by the withdrawing yarn, as indicated above, causes it to extend between the cutting blades under the tines of the spring clamp 86 beneath which it passes due to engagement by the projecting upturned ends of the tines and also extends beneath the clamp 88 as indicated in Fig. 14. Immediately thereafter the lever end 108 clears the lever 98, permitting the clamp to snap shut and the cutter to sever 25 the outgoing yarn the end of which is thereafter held by both spring clamp 86 and the clamp lever 89.

The carriage 32 then reaches its extreme forward position causing the bell crank 12 corresponding to finger 4 to pass beyond its latch 23 to be later held thereby. If no selection of yarn is to be made in the formation of the next course, all of the parts are then in their normal positions and as the roller rides down 35 the trailing end of cam 69 over which it snaps after it reaches the position 680, the frame 32 will be retained against another rearward movement by engagement of the latch 45 with projection 47. On the other hand, if the selector 40 arm 46 has in the meantime assumed a position to effect another yarn change, the cycle just described is repeated to introduce the newly selected yarn.

It will be noted from the above that due to 45 the downward and then upward movements of the blocking pins 111 and 112, there is a slight interval during which both the incoming and outgoing yarns are being taken by the needles. This produces the necessary overlap of a few 50 needles to produce knitting continuity.

One of the important features of this yarn changer is the fact that unlike changers heretofore used, the yarn finger movement has nothing whatever to do with determining the needle on 55 which a yarn is to enter or the needle on which it is to leave. Regardless of which finger is going into action, the yarn is always carried to the same needle by the same element, namely, the placer 122, and likewise, regardless of which 60 finger is being moved from feeding position, the yarn always leaves at the same needle, being controlled by the same element, namely, the blocking pin 111. The placer 122 and the two blocking pins which control all the successive events 65 in the yarn replacements are extremely light and, due to their actuation by the tripping of various elements by the lever 103, are moved with great rapidity so that, despite the continued high speed of the needle cylinder, the replacements take 70 place with great accuracy, the yarn change laps having a constant width and being on the same wales, with the result that a more pleasing appearance is provided. Adjustments of the various cam ends 142 and 108, screw 116, screw 105, 75 etc., provide for the necessary fine adjustment

to secure precisely the sequence of events and overlap which are desired.

It has been found that the upper block pin 111 may possibly be omitted and that nevertheless overlap can be secured through the precise actuation of the placer finger 122. However, greater accuracy is secured by depending upon movement of placer 122 to determine the precise instant at which yarn is taken by a predetermined needle and by depending upon the rise of blocking pin 111 to determine the precise withdrawal 10 of the outgoing yarn from a subsequent needle.

It will be obvious that various details of construction may be changed without departing from the scope of the invention.

What I claim and desire to protect by Letters Patent is:

1. In a circular knitting machine, in combination, needles, a yarn finger adapted to feed a 20 yarn to the needles from a feeding position, means for withdrawing said yarn finger from its feeding position outwardly and forwardly with respect to the needle rotation relative to its feeding position, and yarn controlling means adapted to maintain said yarn in substantially normal 25 feeding relationship with the needles as its finger is being so withdrawn.

2. In a circular knitting machine, in combination, needles, a plurality of yarn fingers each being 30 adapted to feed a yarn to the needles from approximately the same feeding position, means for substituting and withdrawing said yarn fingers selectively in and from said feeding position in arbitrary order, and yarn controlling means adapted to maintain each of said yarns in substantially normal feeding relationship with the needles as its finger is being withdrawn irrespective of the finger being substituted therefor.

3. In a circular knitting machine, in combination, needles, a plurality of yarn fingers each being adapted to feed a yarn to the needles from approximately the same feeding position, means for so withdrawing said fingers from said feeding position that their yarn feeding ends move 40 in different paths to clear each other, and yarn controlling means adapted to maintain each of said yarns in substantially normal feeding relationship with the needles as its finger is being withdrawn. 45

4. In a circular knitting machine, in combination, needles, a plurality of yarn fingers each being adapted to feed a yarn to the needles from approximately the same feeding position, means for substituting and withdrawing said yarn fingers selectively in and from said feeding position in arbitrary order, and yarn controlling means adapted to maintain each of said yarns in substantially normal feeding relationship with the needles as its finger is being withdrawn irrespective of the finger being substituted therefor, and subsequently to release said yarn so that 50 it is no longer fed to the needles.

5. In a circular knitting machine, in combination, needles, yarn fingers adapted to feed yarns to said needles, a yarn clamp for holding the inactive yarns, yarn controlling means adapted to maintain a yarn in feeding relationship with the needles when its finger is being withdrawn, yarn finger operating means adapted first to withdraw a finger from feeding position and then to insert another finger in said feeding position while said yarn controlling means is maintaining the active yarn in feeding relationship with the needles, a yarn placer adapted to engage the 65 70 75

- yarn extending from the newly introduced finger to the clamp and carry it over to the needles, and means for so manipulating the yarn controlling means that it will not interfere with the yarn being presented to the needles.
6. In a circular knitting machine, in combination, needles, yarn fingers adapted to feed yarns to said needles, a yarn clamp for holding the inactive yarns, yarn controlling means adapted to maintain a yarn in feeding relationship with the needles when its finger is being withdrawn, yarn finger operating means adapted first to withdraw a finger from feeding position and then to insert another finger in said feeding position while said yarn controlling means is maintaining the active yarn in feeding relationship with the needles, a yarn placer adapted to engage the yarn extending from the newly introduced finger to the clamp and carry it over to the needles, and means for so manipulating the yarn controlling means that it will not interfere with the yarn being presented to the needles and will subsequently release the outgoing yarn after the newly introduced yarn has been engaged by the needles.
7. In a circular knitting machine, in combination, needles, yarn fingers adapted to feed yarns to said needles, selective means for withdrawing fingers from and inserting them in yarn feeding position in arbitrary sequence and means acting on the yarns between said fingers and said needles to control said yarns to introduce them on a certain one of the needles and to withdraw them from another certain one of the needles.
8. In a circular knitting machine, in combination, needles, yarn fingers adapted to be moved into and out of feeding relationship with the needles in arbitrary selective sequence and means independent of said fingers and said needles and acting on the yarns between the fingers and needles to control the yarns feeding from said fingers to engage them with a certain one of the needles and to withdraw them from a certain one of said needles.
9. In a circular knitting machine, in combination, needles, yarn fingers adapted to be moved into and out of feeding relationship with the needles in arbitrary selective sequence and means independent of said fingers and said needles and acting on the yarns between the fingers and needles to control the yarns feeding from said fingers to engage them with a certain one of the needles and to withdraw them from a certain one of said needles, so that the yarn change laps extend across the same needle wales.
10. In a circular knitting machine, in combination, needles, yarn fingers movable into and out of yarn feeding position, means to so move the fingers including operators, one for each finger, which move in unison with each other when a yarn change is to take place, each operator adapted to be positioned to either move its respective yarn finger into feeding position or out of feeding position, and means for selectively positioning the operators prior to their said movements.
11. In a circular knitting machine, in combination, needles, a plurality of yarn fingers adapted to feed yarns to the needles, yarn finger operating means, means for clamping inactive yarns, and means for controlling the feed of yarns to the needles, said last means comprising a plurality of pins successively active to maintain an outgoing yarn in feeding relationship to the needles for a predetermined period following beginning of withdrawal of its finger.
12. In a circular knitting machine, in combination, needles, a plurality of yarn fingers adapted to feed yarns to the needles, yarn finger operating means, means for clamping inactive yarns, and means for controlling the feed of yarns to the needles, said last means comprising a plurality of overlapping pins successively active to maintain an outgoing yarn in feeding relationship to the needles for a predetermined period following beginning of withdrawal of its finger.
13. In a circular knitting machine, in combination, needles, a plurality of yarn fingers adapted to feed yarns to the needles, yarn finger operating means, means for clamping inactive yarns, and means for controlling the feed of yarns to the needles, said last means comprising a plurality of pins arranged across the paths of incoming and outgoing yarns, one of said pins being closer to the needles than the other, and means for actuating said pins to successively cause the first pin to release the incoming yarn to feeding position and the outgoing yarn to an inner position in engagement with the second pin to continue to feed to the needles and then cause the second pin to release the outgoing yarn to cause its withdrawal from the needles.
14. In a circular knitting machine, in combination, needles, yarn fingers adapted to feed yarns to the needles, a movable carriage, yarn finger controlling elements, individual to the fingers, mounted on said carriage, spring means for moving said carriage, and a member alternatively operable to hold said carriage against movement by the spring means or to selectively control said elements during such carriage movement to effect a yarn change.
15. In a circular knitting machine, in combination, needles, yarn fingers adapted to feed yarns to the needles, a movable carriage, yarn finger controlling elements, individual to the fingers, mounted on said carriage, a cam follower lever for controlling movements of the carriage, and cam means for alternatively actuating said lever to produce either slight movement of the carriage or a complete yarn changing movement thereof.
16. In a circular knitting machine, in combination, needles, yarn fingers adapted to feed yarns to the needles, a movable carriage, yarn finger controlling elements, individual to the fingers mounted on said carriage, spring means for moving said carriage, a member alternatively operable to hold said carriage against movement by the spring means or to selectively control said elements during such carriage movement to effect a yarn change, a cam follower lever for controlling movements of the carriage, and cam means for alternatively relieving said member of its carriage holding function or for controlling a yarn changing movement of the carriage.
17. In a circular knitting machine, in combination, circularly arranged needles, a plurality of yarn fingers adapted to feed yarns to the needles, a yarn clamp for holding the inactive yarns, operating means adapted to locate a yarn finger in feeding position so that the yarn carried by said finger extends from the finger to the clamp, a yarn placer, and means adapted to first positively move said placer in the direction of the axis of the circle of needles to the yarn engaging level and then to swing it transversely to said axis to engage the yarn extending between the finger and the clamp and carry it over to the needles so that it may be engaged thereby.

18. In a circular knitting machine, in combination, needles, yarn fingers adapted to feed yarns to the needles, a movable carriage, yarn finger controlling elements mounted on said carriage, a lever for moving the carriage, a slideable cam follower carried by said lever, two cams for controlling the lever, and means adapted to slide the follower from one cam to the other. 5
19. In a circular knitting machine, in combination, needles, yarn fingers adapted to feed yarns to the needles, a movable carriage, yarn finger controlling elements mounted on said carriage, a lever for moving the carriage, a slideable cam follower carried by said lever, a cam adapted to 10 advance said carriage to effect a change of yarn, said cam having a high concentric portion which maintains the carriage in its extreme forward position, a second cam adjacent to the first cam adapted to prolong the high portion of the first 15 cam, and means for controlling the follower so that it may be under the influence of either one of the two cams. 20
20. In a circular knitting machine, in combination, needles, yarn fingers adapted to feed 25 yarns to the needles, a movable carriage, yarn finger controlling elements mounted on said carriage, spring means for retracting said carriage, an operating lever for advancing said carriage to effect a yarn change, a slideable cam follower carried by said operating lever, two adjacent cams adapted to control the operating lever through 30 said follower, means adapted to selectively control the elements mounted on the carriage, means adapted to hold the carriage in its forward position, and means for moving the follower from one 35 cam to the other so that during the yarn changing movement of the carriage one of the cams will be operative and during the actuation of the selecting means and holding means the other cam will be operative. 40
21. In a circular knitting machine, in combination, circularly arranged needles, a plurality of yarn fingers adapted to feed yarns to the needles, a yarn clamp for holding the inactive 45 yarns, operating means for locating a yarn finger in feeding position so that the yarn carried by said finger extends from the finger to the clamp, a single yarn placer arranged to engage all of said yarns, means for moving said placer from inactive position to engage the yarn extending 50 between a newly introduced yarn finger and the clamp to carry it over to the needles so that it may be engaged thereby, and means for thereafter moving the placer out of the path of a withdrawing yarn prior to the placer's reaching its inactive position. 5
22. In a circular knitting machine, in combination, needles, a yarn finger adapted to feed a 10 yarn to the needles from a feeding position, means for withdrawing said yarn finger from its feeding position, said yarn finger in its withdrawing movement tending to move its yarn both outwardly and in the direction of the axis of the needle circle, and yarn controlling means for preventing both substantial outward and substantial axial movements of the yarn from normal feeding relationship with the needles as its 15 finger is being withdrawn. 15
23. In a circular knitting machine, in combination, needles, a plurality of yarn fingers each being adapted to feed a yarn to the needles from approximately the same feeding position, means 20 for withdrawing said yarn fingers from said feeding position, at least one of said yarn fingers in its withdrawing movement tending to move its yarn both outwardly and in the direction of the axis of the needle circle, and yarn controlling 25 means for preventing both substantial outward and substantial axial movements of the yarns from normal feeding relationship with the needles as their fingers are being withdrawn. 25
24. In a circular knitting machine, in combination, needles, a plurality of yarn fingers adapted 30 to feed yarns to the needles, yarn finger operating means, a clamp for inactive yarns, and means arranged across the paths of the incoming and outgoing yarns to temporarily retain an outgoing 35 yarn in feeding relationship with the needles without interference with engagement of an incoming yarn by the needles. 35
25. In a circular knitting machine, in combination, needles, yarn fingers which are spring urged into feeding position, detents associated 40 with the fingers and adapted to hold said fingers out of feeding position, and an operating element for each finger and detent arranged to occupy alternative positions and adapted to be selectively 45 located in one position to trip a detent out of mechanical connection with its finger and thereby render its finger active or in another position to positively withdraw its finger from feeding position so that it will be held out by its detent. 50

HAROLD E. HOUSEMAN.
